OSCILLATORY VALVE FOR INTERNAL COMBUSTION ENGINES

Curt Bretschneider, Philadelphia, Pa., assignor of twenty-five percent to C. Alexander Hatfield, North Wales, Pa.

Application January 29, 1938, Serial No. 187,612

14 Claims. (Cl. 123—81)

This invention relates to oscillatory valves for internal combustion engines.

It is among the objects of this invention; to provide an oscillatory valve having a cycle of operation in which the valve is expanded to gas tight seating in its relatively stationary positions, with a predetermined loosening of its sealed engagement in the intervals in which the valve is relatively moving; to provide an internal combustion engine with an oscillatory valve of high efficiency and which retains the high efficiency for an unprecedentedly long life; to provide an oscillatory valve requiring little force for its oscillation but which is gas tight when necessary; to provide improved mechanism for actuating an oscillatory valve; to provide a valve which is unprecedentedly free from frictional wear; and many other objects and advantages as will become more apparent as the description proceeds.

In carrying out the invention in a preferred embodiment, an expandable oscillatory valve is disposed in a housing, means are provided to expand and contract the valve in cyclic relation to its oscillations to make it gas tight at desired intervals and free from undue friction during its oscillation.

In the accompanying drawings:

Fig. 1 represents a transverse vertical section, partially in elevation, through an internal combustion engine containing the improved valve of the invention according to one embodiment thereof,

Fig. 2 represents a fragmentary transverse section through the engine of Fig. 1 with two valves shown in section in different positions of adjustment relative to the common port of each cylinder,

Figs. 3, 4, and 5 represent side elevations of pushing and forming elements respectively disposed in Fig. 1,

Fig. 6 represents a plan of the forming element of Fig. 5,

Fig. 7 represents a reflected or bottom plan of the skeleton or forming element of Fig. 5,

Fig. 8 represents a transverse section through the forming element of Fig. 5 taken on line 8—8 thereof,

Fig. 9 represents a vertical section, partially in elevation of the valve element and the actuating cams therefor taken perpendicularly to the section of Fig. 1,

Figs. 10 and 11 represent respectively a plan and a vertical section of the main expandable channel forming valve element, shown in Figs. 1 and 9, showing cam surfaces,

Figs. 12 and 13 represent respectively a plan and vertical section of the upper contractive cam-surface-carrying cooperative element for the channel forming element,

Figs. 14 and 15, and 16 and 17 represent respectively plans and vertical sections of additional lower contractive and expansive cooperative elements for anchored engagement with the channel forming expandable element of Figs. 1 and 9.

Figs. 18 and 19 represent side elevations and bottom plans of one of the cams for oscillating the valve as disclosed in Fig. 9,

Fig. 20 represents an elevation of the central cooperating cam element showing the double cam surface for receiving the alternate thrusts of the inclined cams to secure oscillation of the valve,

Fig. 21 represents an elevation of the double cam by which either expansion or contraction of the oscillatory valve is secured,

Fig. 22 represents a side elevation of the double cam element of Fig. 21,

Fig. 23 represents a fragmentary horizontal section through the engine with the several cam actuated control elements shown in section,

Fig. 24 represents a fragmentary vertical section, partially in elevation, of the upper end of the contracted oscillatory valve, with the upper end of the double cam actuating element in a position contracting the valve, and showing in dotted lines the position of the parts in the expanded position of the valve, in an exaggerated manner,

Fig. 25 represents a fragmentary transverse section through a valve according to this invention in contracted position relative to the walls within which it oscillates, to indicate the minimization of friction secured thereby, and showing in dotted lines the expanded position thereof to tightly sealed position, in an exaggerated manner.

Referring to Fig. 1 the internal combustion engine 10 may be of any desired type having any desired form of power conversion, although for illustrative purposes it will be considered as an ordinary four cycle reciprocating piston type having a cylinder 11, piston 12, connecting rod 13, crank throw 14 and crank shaft 15. Suitable water jacketing 16 will be provided and a combustion chamber 17 will be formed above the piston, in communication with which a spark plug 18 will be provided. The combustion chamber is prolonged laterally in any desired suitable manner into a common channel or port passage 20 55.

leading to a valve chamber 21. The valve chamber 21 and common port or channel 20 are divided into an exhaust passage 22 and an intake passage 23, by the abutment 24 in the common passage, and by the formation of the valve with an abutment end 9 wide enough to close both intake and exhaust ports and with side walls 7 and 8, to be described. The exhaust passage is defined on one side by the abutment 24 and the 10 valve itself (wall 7), and on the other by a wall surface 25. The intake passage is defined on one side by the abutment 24 and the valve itself (wall 8) and by the wall surface 26. At the rear of the valve the wall surface 27 of the engine 15 defines with walls 25 and 26, the valve chamber, and its lateral wall areas 28 and 30 are spaced from the complementary surfaces 25 and 26 respectively to form the respective exhaust and intake conduits 31 and 32, leading to the exhaust manifold, not shown, and to the carburetor or other charge forming device or intake manifold, not shown. The particular mode of providing the explosive mixture forms no part of the present invention.

25 It will be understood that where the cylinders are in multiple, as shown in Fig. 2, the valve sides will be reversed so that two adjacent valves will open upon a single common exhaust channel 31, or upon a single common intake channel 32, as 30 will be clear.

The upper end of the valve chamber 21 is closed by a suitable removable plate 33, which carries a suitable depending anti-friction device 34 which is well lubricated and is capable of adjustment as 35 indicated in Fig. 1, and the plate has suitable lubricating passages 35 through which lubricant may pass in any preferred manner. The anti-friction element such as the rounded ball element on the end of the threaded shank shown, is engaged from below by the upper end 36 of a forming or skeleton element 37, in a recess 38 thereof, and the end 36 is such as to have slidable fit within the valve chamber 21. The lower enlarged end 40 thereof has similar slidable fit in the lower end 45 of the valve chamber. The forming element throughout the length of the valve element itself, is a narrow shank, as at 37, having lateral walls 41 and 42 which are slightly inclined relative to each other, preferably, and has the indented arcuate grooves 43 to receive leaf springs 44, arranged to bear laterally against the inner wall surfaces of the valve element to be described. The shank portion 37 is longitudinally slotted in the rear wall as at 45 to receive the 50 anchoring tongues of valve elements to be described. The lower enlarged portion 40 of the forming element is made hollow for lightness and accessibility of the interior, and has an eccentric slot 46 to receive an end of the double cam element to be described, and has an eccentric bore 47 to receive the short push rod 48 slidably therein, having an edge portion in alignment with the axial bore in the bottom plate surface 51 of the forming element. The lower portion of the forming element is cut away laterally to expose the apertures 52 and is eccentrically vertically notched as at 53 for a driving connection.

The forming element has a rigidly mounted lower extension comprised of the tubular shank 55 (Fig. 20), within which the push rod 56 is slidable to abutment against the tubular eccentric push rod 48 in the forming element, and carries at its upper end the attachment plate 57 arranged to engage against the bottom surface of the plate 75 end 51, with the vertical ears seated in the

notches 53, and anchored by suitable bolts or the like 58 passing through the apertures 52 into the extension plate 57.

Disposed laterally of the junction of the tubular shank 55 with the plate end 57, on each side thereof, is the depending cam device 58, having inclined cam faces respectively 60 and 61. In an aperture 62 in each face perpendicular to the cam face 60 or 61, is the adjusting bolt head or other adjustment wear element 63. Vertical thrust 10 alternately on each face causes oscillation of the valve assembly.

The engine below the valve chamber may be enlarged and provided with a removable plate 64 to facilitate adjustments of the valves, as may be 15 desired, and will have a transverse baffle having constricted or restricted annular journals or bearings 65 to receive and enable rotation of the tubular shank 55 of the lower end of the rigid extension, and bearings provided as at 66, for the vertically reciprocable cam actuating elements respectively 67 and 68. The actuating elements have at the upper end each an inclined cam surface 69 disposed substantially parallel to the respective faces 60 and 61 with which they are each 25 substantially juxtaposed. Each actuator preferably has an internal bore 70 arranged to receive a shock absorbing compression spring 71 and the push rod shank 72, the lower end of which is enlarged as at 73 to engage in the cooperatively 30 enlarged aperture and to serve as the wear element in contact with the juxtaposed cam of the pair of cams 74 and 75. The oscillating cams 74 and 75 are mounted on the cam shaft 76 and separated by the expansion cam 77 with which the 35 axial push rod 56 is in engagement. Obviously the cam disposition will be changed or modified from that disclosed depending upon the variation in timing it may be desired to impart to the valve. It will be clear that upward motion of 40 the cam actuator 67 will cause the cam surface 69 thereof to engage the end of the bolt 63 and to swing the entire assembly of the forming element in one direction. In the cycle of operations the cam 67 will drop away from the bolt head 63 45 and in due course the other cam actuator 68 will rise and its cam face 69 will engage the other bolt head 63 and the forming element will be swung in the other direction.

The forming element as disclosed obviously 50 comprises a mere skeleton upon which elements must be mounted to constitute a valve, although it is contemplated that the valve may be provided as a unitary one piece device if desired. The valve may be formed in many ways, obviously, but 55 in the interest of simplicity of construction and operation an illustrative not limitative embodiment is disclosed. For ease of assembly the valve will be considered as formed of five nesting elements, shown disassembled in Figs. 10 to 17 inclusive, and in nested engagement in Fig. 9. The main valve element comprises a channel member which is internally slotted as at 80 having the longitudinal aligning lug 81 arranged to engage in the forming member slot 45 in assembled 60 relation, upon which member the valve elements all may be mounted by straddling the forming shank as the elements move laterally to seating thereon. The main element has at the top quasi annular plate, baffle or sealing element 82 arranged to seat in the valve chamber 31 to prevent leakage longitudinally of the valve. A complementary slotted plate or sealing element 83 is provided at the lower end, also arranged to sealingly engage in the valve chamber to prevent 65 70 75 75

downward longitudinal leakage from the valve. It will be understood that any desired packing and piston ring dispositions may be used on the plates 82 and 83, as in any other of the relatively 5 movable leak proof connections of the invention.

The lower plate contains a peripheral slot or groove 89 communicating with the opening 88, and is arranged to receive the complementary co-operative ring 85 on the slotted ring 86, and at 10 the upper end the slot 88 communicates with the outwardly flared cam surfaces 87 extending transversely to the lateral end of the legs of the yoke or clevis surrounding the slot 80 to receive the actuating double cam to be described. The 15 upper end of the main valve element has an interrupted axially extending annulus or wall 88, arranged to be embraced by the nested upper complementary valve element 90. The latter is slotted and has at the top a plane surface 91 arranged 20 to slide under the cover plate 33, and has the internal ear or rib 92 to engage in the slot in the shank 37 of the forming member. The upper valve member has the enlarged bottom recess 93 arranged to receive the annular rib 88 25 of the main valve element, and has the inclined milled slots 94 extending from each side of the median lateral slot 95 between the legs of the element. The lower end of the main valve element rests upon the intermediate complementary 30 split or slotted element 86, already mentioned, and the lower end of the latter is provided with the annular end recess 96, and inclined milled cam surfaces 97, and the integral ear or tongue 98, the substantially identical counterpart of the recess 35 93, inclined surfaces 94 and ear 92, of the element 90 just described above. The intermediate member or element in turn rests upon a slotted sub-element 100 having similar contours to the channel element, including the slotted aperture 40 101, the upwardly inclined surfaces 102, the upwardly directed axial annular wall or rib 103 arranged to engage within the recess 96 of the last described sub-element, and the anchoring ear 104. The sub-element 100 has a lower plane face seated 45 upon the upper end of the enlargement 40 of the forming element of the valve, and has recesses 99 housing springs 119.

With the several elements just described in nested relation one with another and pushed laterally onto the forming element shank, as described, it will be clear that a vertical slot will remain eccentric of the valve axis. This is substantially filled with the double cam element to be described. It will be understood that the several components of the valve will have outer dimensions and contours conforming to that of the valve chamber 21 and that for all practical purposes the valve assembly can be considered after assembly as a single entity having a groove or 55 recess shaped to receive a double cam element to be described.

A double cam device is provided comprising a shank 105 having at the lower end a threaded bore 106 to receive an adjustable stop element 107, and is outwardly shaped to be slidably received and guided laterally in the several slots of the valve element and the slot in the forming element in enlargement 40 thereof, and in the direction radial of the piston and cylinder is so 60 shaped as to be slidable between the rear edge of the shank 37, as at 39, and the valve chamber surface of the wall 27. It has its lower end with the adjustable stop 107 in position to be engaged by a portion of the tubular push rod 48, and at 70 the upper end terminates in a substantially cylind-

rical oil conducting plug 108 arranged to embraceably receive a compression spring of desirable strength, as 110, and to be slidably disposed in a guide and lubricator aperture 29 in the top flange or plate 36 of the forming element. To 5 ward the upper end the shank has a pair of laterally upwardly inclined cam arms respectively 111, and 112, having each an upper cam surface 113 arranged to engage the inclined slots 94 of the composite valve to draw the valve legs together to contract the upper portion of the valve, and each has also the lower cam surface 114 arranged to engage the upwardly flared internal surfaces 87 of the main valve element to force the legs of the element outwardly and apart to expand the valve. Toward the lower end the shank 105 has the lower laterally upwardly inclined pair of divergent cam arms 115 and 116 having each upper surfaces 117 arranged to engage the inclined surfaces 97 to draw the lower end of the 10 valve together simultaneously with the upper end, and lower cam surfaces 118 to engage the inclined internal surfaces 102 to spread the lower end of the valve simultaneously with the upper end. 15

With the parts arranged as disclosed it will be clear that as the cams 74 and 75 cause oscillation of the entire valve body, the system of push rods and the cam 77 will positively be impelled upwardly to simultaneously pull the valve toward constructed position at the top and bottom as shown in full lines in Fig. 25, with the double cam element in the position shown in full lines in Fig. 24. At this juncture the coil or compression spring will have been loaded, and pursuant to movement of the cam 77 to a position permitting the system of push rods and double cam elements to move downwardly the coil spring will urge the shank of the double cam downwardly, simultaneously forcing the lower cam faces to 20 engage the juxtaposed valve surfaces to force the valve to expanded position at both the top and bottom. This is indicated in dotted lines in both Figs. 24 and 25. The lateral expansion of the valve is facilitated in case of need by the spring 25 devices 44 as indicated in dotted lines in Fig. 24.

The preferred arrangement of the cams is such that with the piston starting up on compression stroke, the valve will have moved to the middle position as shown at the left of Fig. 2, and in Fig. 25, and in this position simultaneously with its attainment the valve will have been urged to expansion to the dotted line position shown. This gas tight positioning is maintained during the remainder of the compression stroke, through 50 the beginning of the firing or power stroke, toward the lower end of which the contracting cycle of the cams will occur as a result of which the valve will become contracted sufficiently to permit oscillation with a minimum of friction. The 55 contraction of the valve will occur very slightly in advance of the oscillation of the valve toward the right, (Fig. 25), to open the exhaust port, through which the exhaust gases will pass during the small balance of the power stroke, and 60 through the entire exhaust stroke. Then at the climax of the exhaust stroke, at somewhere near approximately top dead center of the piston, with the valve still constricted to prevent frictional binding and wear the valve is suddenly oscillated 65 from exhaust through the slight movement toward intake which maintains while the piston travels to the bottom substantially of the intake stroke, still preferably with the valve in frictionless constricted position. Then toward the 70 75

bottom of the intake stroke, the valve is suddenly oscillated to close both ports, and practically simultaneously therewith, although obviously not prior thereto, the valve is again expanded to the 5 dotted line position of Fig. 25, during compression, and the cycle is complete.

It is pointed out that the showing of Figs. 24 and 25 is highly exaggerated, as it would be difficult to indicate the true but minute expansive 10 movement of the valve elements. It may be noted further that the abutment 24 may be omitted if desired, or it may be made wider or of other changed size if it were desired to reverse the valve element to have the expansive end in engagement 15 with the said abutment. As an element in the assembly it may be noted that this is facilitated if the double cam reciprocatable member 105 is mounted in the forming element before the compound valve element is moved laterally to 20 straddling engagement therewith. The advantage of the illustrated disposition of the valve in place of reversal thereof in place, lies in bringing the adjustment nut or bolt head 107 into juxtaposition to the rear opening through which 25 adjustments can be made with ease, among other advantages.

The further advantages of the invention, as well as the fact that many modifications may be resorted to by those skilled in the art, will be 30 obvious, and such changes are to be construed as within the scope of the invention unless otherwise specifically limited in the attached claims.

I claim as my invention:

1. In internal combustion engines a valve 35 chamber, a valve in the chamber, means for oscillating the valve in the chamber, and means for expanding the valve in the chamber in synchronism with the oscillations thereof.

2. In internal combustion engines, a valve 40 chamber, a valve in the chamber, means for oscillating the valve in the chamber, and means for contracting the valve in the chamber in synchronism with the oscillations thereof.

3. In internal combustion engines, a valve 45 chamber, a valve in the chamber, means for oscillating the valve in the chamber, and means for varying the external size of the valve in synchronism with the oscillations thereof.

4. In internal combustion engines, means defining a common intake and exhaust passage, an oscillatable valve disposed in the common passage and arranged to close both the common intake and the common exhaust in one position, means for expanding the valve in said position to make 55 the valve substantially gas tight, and means for releasing the expanded condition and for oscillating the valve from the said position.

5. In internal combustion engines, a valve 60 chamber, a valve disposed in the chamber and arranged for oscillation, said valve having an axis of oscillation, means carried by the valve including depending inclined faces in substantially common planes, push rods arranged for vertical movement in contact with each face, a cam shaft, and cams in engagement with the push rods for actuating same, the whole constructed and arranged that the valve is swung about its axis alternatively by the vertical thrusts of the push rods.

6. In internal combustion engines, a valve element having a longitudinal slot, means defining a valve chamber and closing said slot, and wedging means reciprocable in the slot for wedging 75 the element to an expanded condition relative to

the valve chamber during the cycle of operation of the engine.

7. In internal combustion engines, means defining a valve chamber having three communicating passages, an oscillatable valve having an axis of oscillation, means for oscillating said valve to successively close communication between the three passages, and to place pairs of passages in communication, and expanding means in synchronism with the engine cycle for urging the valve to gas tight relation to the valve chamber during the interval in which all of the passages are out of communication.

8. In internal combustion engines, means defining a valve chamber having three passages in communication therewith and respectively comprising an exhaust passage, an intake passage, and a common exhaust and intake passage, means for oscillating the valve from a position in which the exhaust and common passage are in communication to a position in which the intake and common passage are in communication and to a position in which the common passage is closed relative to either the intake or exhaust passages, and means for securing a synchronous periodic expansion and release of the valve during the cyclic positioning of the valve.

9. In internal combustion engines, means defining a valve chamber having three passages in communication therewith and respectively comprising an exhaust passage, an intake passage, and a common exhaust and intake passage, means for oscillating the valve from a position in which the exhaust and common passage are in communication to a position in which the intake and common passage are in communication and to a position in which the common passage is closed relative to either the intake or exhaust passages, means for expanding the valve in the valve chamber during the last mentioned position 40 of the valve, and means for contracting the valve in the valve chamber during its oscillatory movement.

10. In internal combustion engines, means defining a substantially cylindrical valve chamber, 45 an oscillatable valve disposed in the chamber and comprising a median position having fluid conduit walls and valve chamber sealing means on each side longitudinally of the said walls, said valve having parallel inclined cam surfaces and 50 a slot with which the surfaces are in communication, a reciprocatable push rod having a laterally extending upwardly inclined cam arm arranged alternately to engage one or the other of said parallel cam surfaces with the push rod 55 disposed in said slot, means for reciprocating said push rod and alternatively expanding and contracting the valve, and means for oscillating the valve in synchronism with the reciprocations of the push rod.

11. In internal combustion engines, means defining a valve chamber, a valve oscillatably disposed in the valve chamber, said valve comprised of a forming member having a relatively narrow shank, a plurality of valve components each having a lateral slot and straddling said shank, means on the valve comprising cam surfaces, a longitudinally slidable element disposed in the slots, a cam carried by said element in position to engage the cam surfaces to selectively expand 70 or contract said valve relative to said slots, and means for actuating said slidable element.

12. In internal combustion engines, means defining an apertured valve chamber, valve means having an axis of oscillation and disposed in the 75

- chamber, means operatively associated with the valve means and including two inclined depending cam faces disposed on opposite sides of said axis, said last mentioned means including a push rod journal concentric to said axis, a cam shaft substantially perpendicular to the said axis, a cam on said shaft in position to actuate a push rod in said journal, oscillation-controlling push rods having a linear motion parallel to said axis and arranged to engage the respective inclined cam faces, and cams on said shaft on opposite sides of the first mentioned cam to engage and actuate said last mentioned push rods to swing the valve.
13. In internal combustion engines, means defining a substantially cylindrical valve chamber, a valve in said chamber having an axis of oscillation, said valve being longitudinally split so as to be capable of distortion, spring pressed means disposed in said split and arranged to urge the valve to one condition of distortion, cam means operatively associated with the said means to move it against the resistance of the spring to urge the valve to another condition of distortion opposite to the first mentioned condition.
14. In internal combustion engines, means defining a valve chamber which is substantially cylindrical in contour having three communicating passages separated by wall areas, a valve substantially U shape in cross section disposed in the chamber and arranged for oscillation with the legs of the U shaped portion engaging one of said areas in every adjusted position, the portion of the valve bridging the legs having such peripheral extent as to simultaneously engage both of said other wall areas in one position of adjustment, means disposed between said legs of the U shaped portion arranged to force them apart and against the first mentioned engaged area to expand the valve to intimate bearing engagement of the bridging portion against the said last mentioned other areas to seal the valve with the passages all out of communication.

CURT BRETSCHNEIDER.
